Attorney

UNITED STATES PATENT OFFICE.

RALPH BROWNSON, OF HASTINGS, MINNESOTA.

MOP.

Application filed May 15, 1925. Serial No. 30,463.

The present invention relates to a mop of the type commonly referred to as a dusting mop.

In the construction of dusting mops it is 5 desirable to have the mop portion thereof readily removable for washing purposes, to have the frame of light and strong construction, and to have it balanced so that when the mop is raised from the floor it will remain 10 in a relatively horizontal position. It is also desirable that the handle shall be able to fold into a line approximately coextensive with the body of the mop so as to permit the mop to be used under articles of furniture 15 which have but a slight clearance from the floor.

An object of the present invention is to make a mop having a light, rigid frame with the handle thereof mounted near the 20 center of gravity of the mop and having a handle which can be swung into a line coextensive with the frame of the mop.

Another object is to make a mop having a pair of extending arms which may be telescopically inserted within a seam on a mop to bind the ends of the frame together and having a handle substantially centrally mounted thereof, which may be swung into a plane coincident with that of the mop 30 frame.

These and other features of the invention, not specifically mentioned, will be more fully brought out in the following description and the accompanying drawings, wherein:

35 Figure 1, is a view in perspective of a mop head made in accordance with the present invention, with a portion of a handle connected thereto broken away.

Figure 2, is a view in top elevation of a 40 frame member.

Figure 3, is a sectional view on the line 3—3 of Figure 1; and

Figure 4, is a view in perspective of a frame member of inverted U-shape.

45 Referring to the drawings in detail, a supporting frame A is made of a piece of strip metal bent to form a rectangular bay 2, the sides thereof being bent outwardly at 3, and the sides thereof bent back upon 50 themselves to form a pair of side members 1 extending beyond the base of the bay 2, as shown in Figure 2. A brace member 4 of inverted U section is positioned within the lower end of the bay 2 and serves as a 55 stop to limit the upward swing of a handle 5. Handle 5 is mounted on a pin 6 riveted

in position to penetrate the sides of the bay 2 and the sides of brace member 4. The handle comprises a wooden member 7 cut to a wedge shape, and strips of sheet metal 8 and 9 are connected to the top and bottom of the wedge-shaped portion of the handle, respectively, by means of rivets 10 penetrating the wooden member 7 and the sheet metal strips. The strips 8 and 9 extend 60 beyond the end of the wedge shaped handle portion and are gripped intermediate a folded strip of metal 11 which is bent to encircle the pin 6. The handle portions are firmly gripped together by means of a bolt 12 65 which firmly engages the parts to hold them in intimate contact after assembly. When it is desired to remove the handle from the head of the mop, this may be readily done by removing the bolt 12 and withdrawing 70 the handle from the folded strip 11.

The frame A is intended to be used in conjunction with a mop head C having a strip 13 which may be of cloth, folded over and connected to strands 14 forming the 75 head of the mop, as by sewing.

To assemble a mop with a frame, each of the open ends 15 of the folded upper portion of the mop is slipped over an end of the strap like frame member A and is drawn 80 into the position shown in Figure 1. When the sides 1 of the frame are fully inserted into the upper folded portion 13 of the mop head, the ends of the members 1 are drawn together in approximately the center of the 85 folded member 13. The mop head may then be secured in place by running a strand 16, by means of a needle, through the folded portion of the mop head to retain the mop head in position on the frame. The ends of 90 the strips 1 are perforated to receive the strand 16. A second strand 17 is passed back and forth across the rear of the mop to hold the mop head securely in position on the frame.

100 The mop, when assembled, is of elongated heart shape. The inverted U-shaped member 4 serves to limit the upward movement of the handle, and permits the nose of the mop to be depressed by raising the handle 105 and pressing down on the mop. The bay 2, being of a size to readily receive the mop handle between the sides thereof, permits the mop handle to be swung down into a plane substantially parallel with that of the mop frame and thereby permits the mop to be 110 used under articles having but a small clear-

ance from the floor. The strand 17 limits the downward pivotal movement of the handle and thereby prevents the reversing of the mop on the handle. This acts to keep 5 the mop constantly in a mopping position with respect to the handle.

What I claim is:

1. A mop, comprising a handle, a frame 10 formed of a single piece of metal having a rectangular bay therein, each side thereof being folded back upon itself to extend beyond said bay, a brace of inverted U-shape mounted transversely of the rectangular bay, a pivot pin mounted transversely of said 15 brace, strip means encircling the pivot pin and connected to the handle, and a mop

fabric including a sheath into which the frame extends with the side portions thereof enclosed.

2. A mop, comprising a handle, a frame 20 formed of a single piece of metal bent to have a bay therein, a pivot pin mounted transversely of said bay, means carried by said handle and encircling said pin to pivotally connect the handle to said pin, and 25 brace means penetrated by said pivot pin and having a transverse portion above the pivot pin to limit the pivotal movement of said handle about said pivot pin.

In testimony whereof I affix my signature.

RALPH BROWNSON.
